A. DE CICILIANI.
CONCRETE BLOCK MAKING MACHINE.
APPLICATION FILED NOV. 27, 1920.

1,375,953.

Patented Apr. 26, 1921.

INVENTOR:
ANTONY DE CICILIANI,

By:

Ollie D. Rueger
his Atty.

UNITED STATES PATENT OFFICE.

ANTONY DE CICILIANI, OF LOS ANGELES, CALIFORNIA.

CONCRETE-BLOCK-MAKING MACHINE.

1,375,953.

Specification of Letters Patent. Patented Apr. 26, 1921.

Application filed November 27, 1920. Serial No. 426,832.

To all whom it may concern:

Be it known that I, ANTONY DE CICILIANI, a citizen of Jugoslavia, residing at Los Angeles, in the county of Los Angeles and 5 State of California, have invented a new and useful Concrete-Block-Making Machine, of which the following is a specification.

This invention relates to devices for making concrete blocks.

10 One of the objects of this invention is to provide a machine in which concrete blocks of various sizes can be made.

Another object is to provide a machine in 15 which a variety of cores can be used without material changes of the machine.

Another object is to provide a machine in which one lever actuates the several doors and cores from a fully closed position to a fully open position, and from a fully open to 20 a fully closed position, so that, on setting the lever for the closed position, the doors and cores are firmly held in position to receive the concrete, while, on setting the lever for the open position, all the doors and cores 25 are suitably moved away from the finished concrete block that the block may easily be removed from the device.

Other objects will appear from the following description and appended claims as well 30 as from the accompanying drawing, in which—

Figure 1 is a perspective view of the complete device in closed position, ready to receive the concrete.

35 Fig. 2 is a detail end elevation of the front door with the operating lever attached and in operating position.

Fig. 3 is a top plan view of one of the side doors with a portion of the connecting and 40 operating rod connected.

Fig. 4 is a detail fragmentary end elevation of the guiding members of the cores.

Fig. 5 is a detail side elevation of a core 45 attached to the guiding member.

The base frame 6 supports the whole device and forms the stationary member. The rear body plate 7 is preferably firmly secured to the base frame. The side doors 8 and 9 are hingedly engaged with the rear 50 plate 7, as indicated at 10. The shaft 11 is turnably mounted on the front side of the base frame. The front door 12 is provided with lugs 13 securely pinned to the shaft 11, as indicated at 14. A shaft 15 is turnably

mounted near the upper edge on the front 55 door 12. The operating lever 16 and the hook and closing or locking lever or bar 17 are securely pinned to the shaft 15, as indicated at 18.

Operating the operating lever 16 produces a turning of the shaft 15 and thereby 60 an unlocking or operating movement of the locking bar 17.

Moving or operating the front door 12 produces a turning of the shaft 11. 65

The operating lever 16 is provided with an extension end 19. This end is provided with a perforation or hole 20, and near the hole 20, a chain or other similar flexible member 21 is provided for holding a pin 22. 70

In operating this device, the operating lever is moved upwardly so as to bring the extension end 19 in alignment with the end of the door 12, as illustrated in Fig. 2, the pin 22 being inserted through the hole 20 in the end 19 into the hole 23 of the door 12 so that the lever 16 projects rigidly in 75 the direction along the edge of the end of the door. The lever 16 engages through the shaft 15 and through the pin 22 rigidly with 80 the door so as to form a suitably long lever on the shaft 11 for operating the shaft 11.

When the lever 16 is so operated, the door 12 is swung open or closed, depending on how the lever is moved. The front end 85 24 of the lever 16 forms the handle of the device.

A lever 25 is securely pinned to the shaft 11 as indicated at 26. A connecting rod 27 connects with the lever 28. The lever 28 is 90 securely pinned to the shaft 29 as indicated at 30. Movement of the shaft 11 is transmitted through the lever 25 and through the connecting rod 27 to the lever 28 and thereby to the shaft 29. A lever 31 is securely 95 pinned to the opposite end of the shaft 29 as indicated at 32.

The levers 28 and 31 connect through connecting rods 33 with the end doors 8 and 9. The movement of the operating lever 16 is 100 in this manner transmitted through the front door 12, the shaft 11, the lever 25, the rod 27, the levers 28 and 31, and through the rods 33 to the side doors 8 and 9.

For molding concrete blocks, it is usually 105 desirable to have suitable side plates in the device provided with the desired facing or impressions wanted on the finished block.

Such plates or pallets are indicated at 34, 35, 36 and 37, and they are normally secured to the doors and stationary plates of the device so as to move with the doors.

5 A core member 38 is illustrated in the drawing, but it will easily be understood that any number of such cores can be used for making hollow blocks. I prefer to have these cores disposed in a horizontal plane so 10 as to bring the face of the block in the bottom or in the top surface, allowing the face to settle. These cores are shiftable to be disposed in the device before the concrete is poured into the device, and to be withdrawn from the device before the finished block is removed from the device.

The outer walls, made up of the rear stationary plate 7, the side doors 8 and 9, and the front door 12 are provided for the 20 purpose of holding the sides firmly together, and therefore are not required to be particularly tight (air-tight, water-tight, etc.), but the inner plates 34, 35, 36 and 37 are closely fitted to prevent leakages when the 25 concrete is poured into the device. The plate 34 on the front door 12 and the plate 37 on the rear plate 7 are therefore provided with openings 39 snugly fitting around the core 38 just loose enough to 30 allow a shifting of the core in the manner described above. The core 38 is preferably secured to a guide member 40 for holding the core in the horizontal plane after the front end leaves the front face plate 34 35 and for more steadily and evenly operating the core in the shifting movements. To make the sliding and shifting movements quite easy and to overcome friction of sliding members, rollers 41 are provided on 40 the guiding frame or member 40, see Figs. 4 and 5. Bracing and supporting arms 43 are provided, having a channeled face 42 for guiding the rollers 41 in their horizontal shifting movements.

45 The connecting rod 44 connects the guiding member 40 with the lever 45. The lever 45 is securely pinned to the shaft 29, as indicated at 46, so that the movement of the operating lever 16, which has so far been 50 traced and explained above up to the shaft 29, is also transmitted to the core 38.

The operating lever 16 controls in this manner all the movements of all the doors and all cores, so that, by a forward and 55 closing movement of the lever 16, all doors are closed and the cores (depending on how many cores are required for certain blocks as explained above) are all securely disposed within the device, making the whole 60 device ready to receive the concrete; while, by a rearward and opening movement of the lever 16, all doors and cores are moved so as to free the finished block so that the 65 finished block may easily be removed from the device.

Having thus described my invention, I claim:

1. In a block-making machine, in combination with opening doors, a lever mounted on one of the doors having means for engaging the lever to the door so as to use the hinge of the door for the operating pivot of the lever in operating the device. 70

2. In a block-making machine, a base member, a front door swingably connected to the base member for a swinging movement in a vertical plane, side doors swingably connected to the base member for a swinging movement in a horizontal plane, a stationary rear plate extending from the base plate upwardly, and an operating lever swingably mounted on one of the doors having means for using the length of the door as a portion of the lever for operating the device and having other means for holding all doors in a closed position. 85

3. In a block-making machine, a base member, a front door hingedly connected to the base member, two side doors hingedly connected to the base member at about right angles to the front door, a rear plate mounted on the base member to be stationary with the base member, and an operating lever on the front door for operating the doors and for holding the doors together in a closed 95 position. 90

4. In a block-making machine, a base member, a shaft turnably mounted on the front of the base member, another shaft mounted on the rear of the base member, 100 a front door mounted on the front shaft, a rear plate mounted on the base member to form a stationary member with the base member, two side doors hingedly mounted on the stationary part of the device, a core 105 member disposed shiftably in the device, and connecting members on the shafts so as to provide a uniform movement of all movable parts of the device when the front door is operated. 110

5. In a block-making machine, a base member, a stationary plate mounted on the base member to form an integral piece with the base member, a front door hingedly connected with the base member for a swinging movement in a vertical plane, side doors hingedly connected with the stationary part of the device for a swinging movement in a horizontal plane, a core member disposed shiftably in the device, and operating means 115 interconnecting the doors and the core so that all parts are handled by the operation of the front door. 120

6. In a block-making machine, a base member, a rear plate extending upwardly 125 from the base plate forming the stationary part with the base member, a front door hingedly connected to the base member for a swinging movement in a vertical plane, a pair of side doors hingedly connected 130

to the rear plate for a swinging movement in a horizontal plane, a core member, an operating lever on the front door, and connecting means for interconnecting the doors 5 and core with the operating lever.

7. In a block-making machine, a base member, a rear plate extending upwardly from the base member forming the stationary part of the device with the base member, a front door hingedly connected to the base member for a swinging movement in a vertical plane, side doors hingedly connected to the rear plate for a swinging movement in a horizontal plane, a number 10 of cores disposed slidably in the device for a shifting movement in a horizontal plane, an operating lever mounted on the front door 15

along one of the upright edges having its pivot point near the top of the front door and having means for engaging along the 20 upright edge of the door so as to make the front door and the lever one member for swinging on the door hinge, and operating means for interconnecting the front and side doors with the cores for handling all 25 members by the operating lever.

In testimony that I claim the foregoing as my invention I have signed my name in the presence of two subscribing witnesses.

ANTONY DE CICILIANI.
